Reg. Sept. 27, 1871.

UNITED STATES PATENT OFFICE.

WILLIAM H. GRIFFITH, OF NEW YORK, N. Y.

DESIGN FOR A BILLIARD-TABLE.

Specification forming part of Design No. 5,322, dated October 24, 1871.

To all whom it may concern:

Be it known that I, WILLIAM H. GRIFFITH, of the city of New York, in the county and State of New York, have invented a new and original Design for Billiard-Tables; and I do hereby declare that the following is a full, clear, and exact description thereof, which will enable others skilled in the art to make and use the same, reference being had to the accompanying drawing forming part of this specification.

The drawing represents a sectional perspective view of my invention.

This invention relates to a new form for the side and end pieces of a billiard-table; and consists in forming a vertical lower portion on the inclined main part of the same.

The face *a* of the side or end piece A is inclined as usually, so that its upper edge is most

forward. The lower part *b* of the said piece, however, is made vertical, and forms an obtuse angle with the face *a*, as shown. A suitable molding, *c*, is affixed at this angle, and another molding, *d*, at the lower part of *b*.

By the application to the inclined face *a* of the lower vertical face *b* a peculiar novel appearance of billiard-table and pleasant effect is obtained.

I claim as my invention—

The vertical part *b* and moldings *c d*, combined, as described, with the ordinarily-inclined part *a* to form a new design for the side and end pieces of a billiard-table.

WM. H. GRIFFITH.
